UNITED STATES PATENT OFFICE

JOHN A. H. SIERS, OF JERSEY CITY, NEW JERSEY

DOORCHECK

Application filed December 22, 1931. Serial No. 582,542.

This invention relates to devices for producing a spring action to close a door, and also a device provided with an air cushion to prevent the slamming of a door when it is being closed.

The object of the present invention is to produce a door check which is simple in construction, easy to manufacture and install, and one that will be durable, smooth in action, and one that does not require a contained liquid to control its action.

For a detailed description of one form of my invention, which I at present deem preferable, reference may be had to the following specification and to the accompanying drawing, in which

Fig. 1 is a vertical sectional view of my improved door check showing the actuating parts thereof in full lines;

20 Fig. 2 is a cross sectional view on 2—2, Fig. 1;

Fig. 3 is a vertical sectional view of the plunger forming the pneumatic buffer, as illustrated in Fig. 1, and

25 Fig. 4 is a plan view of the door check, as installed.

Referring to Fig. 1, the numeral 1 indicates an outer substantially cylindrical casing having the cap 2 for the upper end thereof, and provided with downwardly projecting tapering lugs 3, which engage off-sets 5 forming stops on the interior of the plunger 5, preventing the latter from turning with the spindle 11. The cap 2 is also provided

30 with an opening 4 through which the air may enter and escape. The plunger 5 is provided with a central tubular portion 6, provided with screw threads 7 of comparatively steep pitch, as indicated in Fig. 3. The plunger 5

40 may be provided with packing rings 8 if desired. Surrounding the tubular portion 6 of the plunger 5 is a helical compression spring 9, the top of which contacts with the cap 2 and the bottom of which rests on the

45 inner surface of the end of the plunger 5. The screw threaded portion 7 on the tubular portion 6 of the plunger 5 is adapted to engage corresponding screw threads 10 on a central spindle 11. Said spindle has a bearing

50 in the cap 2 and projects above the same

so that it may be affixed to a suitable lever 12, which is pivoted to an adjustable connecting rod 13, the outer end of which is also pivoted at 14 to the door casing 15.

The casing 1 is affixed to the door in any suitable way, such as by screwing the ears 16 to the door itself. The lower end of the outer casing 1 is provided with a needle-valve or similar device 17, by the adjustment of which the escape of air from the space between the plunger 5 and the lower end of the casing 1 may be regulated. Said end of the casing 1 is also provided with a check valve 18 made in any suitable way, such as by providing a ball 19 held in position by spring 20.

It will thus be seen that when the door is being opened the lever 12 will cause the spindle 11 to rotate on its axis for a distance of 180 degrees, more or less. This will cause the screw threads 10 to draw the tubular portion 6 of the plunger 5 upward, and also will compress the spring 9. When the door has reached the limit of its opening movement, and is released, the spring 9 will force the plunger 5 downward and so compress the air in the space between the end of said plunger and the end of the casing 1. This compression of the air will force air outward through the passage leading to and past the needle-valve 17, and the rapidity of the passage of said air and the rapidity of the closing of said door will be controlled by the position of the screw member of the needle-valve 17. The door will thus be caused to shut slowly and quietly as the frame of the door approaches the door casing, and any slamming action will thereby be prevented. When the door is again opened the plunger will again be drawn upward and the air allowed to enter the end of the casing 1 through the check valve 18.

It will be noticed that the action of my improved door check depends practically upon only two moving parts, that is, parts constituting the screw threaded spindle 10 and the screw threaded tube 6. The screw threads may be made to accurately fit each other, but on the other hand any considerable wear by constant opening and closing of the door will not materially affect the action of the device as a whole. There are therefore

practically no parts to become displaced and no parts to require renewal, thus assuring durability, efficiency and accuracy of action.

The effect of the lugs 3 when opposed by the off-sets 5' will be to prevent the piston 5 from rotating on its axis through friction between the external and the internal threads either when the door is being opened or when the spring 9 is causing the closing action by 10 producing a rotation of the spindle 11.

What I claim and desire to protect by Letters Patent is:

1. A pneumatic door check comprising, a casing having a space forming an air chamber 15 at the lower end thereof, a longitudinally slidable plunger therein, a spring within said casing for producing a pressure upon said plunger, a screw threaded spindle engaging said plunger for moving the same longitudinally, means connected with said spindle 20 for rotating the same by relative motion between a door and its casing, and valves in the wall of said casing for controlling the flow of external air into and out of the door check during opening and closing motions of the door.

2. A pneumatic door check comprising, a casing having a space forming an air chamber at the lower end thereof, a longitudinally 30 slidable recessed plunger therein, an interiorly screw-threaded tube carried by said plunger, a helical compression spring surrounding said tube within said recess and bearing directly on said plunger to force the latter 35 downward, a spindle having steep screw threads thereon and engaging said screw-threaded tube, a lever connected with said spindle for rotating the same by relative motion between the door and its casing, and 40 valves in the wall of said casing for controlling the flow of external air into and out of said casing.

3. A pneumatic door check comprising, a casing having a space forming an air chamber 45 at the lower end thereof, an interiorly screw-threaded member carried by said plunger, a helical compression spring surrounding said member within said plunger and bearing directly on said plunger to force the latter 50 downward, a rotatable member having screw threads thereon and engaging said first screw threaded member, a lever connected with said spindle for rotating the same, stops on said plunger, downward projections on the top of 55 said casing adapted to contact with said stops to prevent rotation of said plunger, and valves for controlling the flow of external air into and out of said casing, respectively.

Signed this 19th day of December, 1931.
JOHN A. H. SIERS.
